ELECTRICAL CONNECTER

Carl H. Bissell, Syracuse, N. Y., assignor to
Crouse-Hinds Company, Syracuse, N. Y., a corporation of New York

Application September 9, 1935, Serial No. 39,755

3 Claims. (Cl. 173—332)

This invention relates in general to electrical connectors, and more particularly to an electrical connector for detachably connecting two electrical conductors together.

The invention is particularly useful for detachably connecting a ground wire to a gasoline tank truck, or the like. It is a matter of common knowledge that the continuous movement of gasoline in a metallic tank truck, which is insulated from the ground by its rubber tires, builds up an electrical charge in the truck of appreciable high potential. This obviously presents a hazardous situation, inasmuch as any connection between the tank and the ground, suitable to pass an electric current, is apt to result in a spark caused by such electrical discharge and cause the tank of gasoline to become ignited. This situation is partially overcome by securing a metallic chain to the truck, permitting the free end to drag upon the road, thereby effecting a path for the continual discharge of the high potential generated by the movement of the gasoline. However, in a number of municipalities the use of the chain as a ground medium is prohibited. Also, it is known that gasoline flowing free in the atmosphere, for example flowing out of a hose or pipe, will generate an appreciably high voltage which, if not immediately and suitably conducted to ground, may cause a spark resulting in a serious explosion.

An object of this invention is an electrical connector which may be quickly and conveniently attached to some suitable portion of the truck, as for example by a snap action, and which is also connected to a wire properly grounded.

A further object of this invention is a connector of the type referred to which, by its construction, will not be damaged in the event the driver, or operator, forgets to disconnect the ground wire before he drives off with the truck.

A further object of the invention is a connector of the type referred to which consists of a minimum number of parts, and is so designed that it may be readily and quickly connected to the ground wire of the electrical system.

The invention consists in the novel features and in the combinations and constructions hereinafter set forth and claimed.

In describing this invention, reference is had to the accompanying drawing in which like characters designate corresponding parts in all the views.

Figure 1 is a plan view of the electrical connector showing a portion of the conductor and ground wire to which it is connected.

Figure 2 is an inverted plan view of the connector.

Figure 3 is an end elevation on lines 3—3, Figure 2.

Figure 4 is a lengthwise sectional view of the parts shown in Figure 1, being taken on line 4—4, Figure 1.

As here shown, the body of the connector comprises two sections 10 and 11. These sections are substantially semi-circular in cross section. The sections 10 and 11 are preferably formed of cast metal and the lower or main section 10 is formed at one end with a rigid jaw designated generally as 12, and with a pair of spaced apart upwardly extending bosses 13 located adjacent the base portion of the jaw 12. The upper body portion 11 is provided at one end with a boss 14 which is arranged between the upstanding bosses 13 and is pivoted to the same by a suitable pin or rivet 15, whereby the rear end of the body section 11 may be swung upwardly away from the rear end of the body section 10 about the pivot 15. The rear end portions 16, 17, of the body sections 10, 11, respectively, are in the nature of substantially flat bosses extending outwardly from the body sections 10, 11, and are formed with complementary semi-circular recesses to form a constricted opening 18 through which the ground wire W is brought into the body of the connector. The end portions 16, 17, act in the nature of a wire or cable grip, and the inner complementary faces are provided with one or more inwardly extending ribs 19. The upper body section 11 is held in clamped engagement with the ground wire by screws 20 located on each side of the passage 18. As here shown, the screws 20 pass through suitable apertures formed in the rear end portion 17 of the section 11 and thread into section 16 of the section 10.

The rigid jaw 12 is formed with a transversely extending groove 21, and the forward portion of the jaw tapers downwardly and forwardly, as at 22.

A binding screw 23 is threaded into the underside of the body section 10 adjacent the base of the rigid jaw 12, and the section 10 is provided with an aperture 24 to permit the bare end of the ground wire W to be looped under the head of the binding screw 23.

Preferably, the jaw 12 is formed with a lengthwise extending rib 25 arranged on each side of the jaw. This rib adds materially to the rigidity of the jaw 12, and also acts as a guard or protection for the head of the binding screw 23.

In order that the connector may be quickly

attached to a conductor, or some suitable part of the gasoline tank truck, the upper body section 11 carries an opposing jaw 27. This jaw 27 is in the nature of a flat metallic spring, the inner end of which is connected to the rear portion of the body section 10 as by rivets, welding or etc., and the outer end of the jaw 27 is curved upwardly or away from the jaw 12, as at 28. With this construction, the connector may be quickly attached to the conductor by simply pushing the outer ends of the jaws 12, 27 against the conductor, with the result that the jaw 27 will spring upwardly or away from the jaw 12, and permit the conductor to enter between the jaws and snap into the transverse groove 21 in the rigid jaw 12. The conductor, to which the connector is attached, may be in the nature of a ring or eye member 30 attached to a portion of the truck frame 31, as by rivets 32. Generally, at filling stations where the tank trucks are filled from large gasoline tanks holding several thousand gallons, and at service stations where the gasoline is transferred from the tank truck to the underground tanks of the service station, it has been common practice to ground the frame of the truck before transfer of the gasoline into the tank truck, or from the same. In these instances, the ground wire has been clamped, in one manner or another, to the frame of the truck and consuming an appreciable amount of time on the part of the operator and then after the tank has been either filled or emptied, the driver forgets to disconnect the ground wire and starts to drive the truck away, with the result that the ground cable is either broken, or the electrical system to which it is attached is damaged.

It will be observed that with my connector, if the truck is driven away, the resilient jaw 27 permits the ring 30 to ride upwardly out of the transverse groove 21 of the rigid jaw, and due to the fact that the ground wire or cable W is securely gripped between the rear end portions 16, 17, there is no possibility of breaking the electrical connection between the wire and the body of the connector. It will also be noted that it is an extremely simple matter to connect the ground wire to the section 10 by simply removing the screws 20 which permits the entire upper body section 11 to be swung out of the way, whereby the end of the ground wire W may be

quickly secured under the head of the binding screw 23, the body section 11 swung toward the section 10, and the ground wire clamped between the end portions 16, 17, by tightening the screws 20.

What I claim is:

1. An electrical connector for detachably connecting a cable to a conductor comprising a body provided at one end with a rigid jaw, a member pivoted at one end to the body between the ends thereof, said member being movable about its pivot to bring the free end thereof into juxtaposition with the end of the body opposite to said rigid jaw to clamp the cable to the body, a resilient jaw carried by said member and arranged in opposed relation to said rigid jaw when said member is in cable clamping position to retain the conductor in frictional engagement with said jaw, means for electrically connecting the cable to the body, and means operable to maintain said pivoted member in cable clamping position.

2. An electrical connector for detachably connecting a cable to a conductor comprising a body provided with a rigid jaw and being formed with a recess extending from the base of said jaw to the opposite end of the body, a member pivoted to the body adjacent the base of said jaw and being movable about its pivot toward the body to form a cover for said recess and to bring the free end of said member into juxtaposition with the end of the body to clamp the cable to the body, a resilient jaw carried by said member and extending in opposed relation to said rigid jaw to frictionally retain said conductor in engagement with the rigid jaw, and means operable to maintain said pivoted member in cable clamping position.

3. An electrical connector for detachably connecting a cable to a conductor comprising a body provided with opposed jaws yieldingly separable to receive the conductor snap fashion, said body being provided with a recess extending lengthwise thereof, a member pivoted to the body and being movable about its pivot toward the body to form a cover for said recess and to clamp the cable to the body, means for electrically securing the cable to the body, and means operable to maintain said pivoted member in cable clamping position.

CARL H. BISSELL.
